Primary Examiner — Cynthia Underwood

CLAIM

We claim the ornamental design for an electronic device folder, as shown and described.

DESCRIPTION

FIG. 1 is a front perspective view of a electronic device folder; FIG. 2 is a back elevational view thereof; FIG. 3 is a front elevational view thereof; FIG. 4 is a left elevational view thereof; FIG. 5 is a right elevational view thereof; FIG. 6 is a top plan view thereof; and, FIG. 7 is a bottom plan view thereof.

The evenly spaced broken lines that follow the perimeter of the electronic device folder represent stitching and are part of the claimed design. Broken lines shown in the three indented or cut-out portions (two shown in FIG. 5 on the right side of the folder, and one shown in FIG. 6 on the top side of the folder) of the perimeter of the folder represent environmental structure, particularly edges of material which are connected together with the illustrated stitching. The non-stitching broken lines form no part of the claimed design.
